FENCE SECTION

John S. Case, Towson, Md., assignor to Anchor Post Products, Inc., Baltimore, Md., a corporation of New Jersey

Filed Mar. 15, 1962, Ser. No. 69,274

Term of patent 14 years

(Cl. D28—1)

FIG. 1

FIG. 3

FIG. 1 is a front perspective view of a fence section showing my new design;

FIG. 2 is a top plan thereof; and

FIG. 3 is a perspective view of a panel used in said fence section of FIG. 1.

The opposite side of the fence section is substantially the same in appearance as the side of the fence section shown in FIG. 1 of the drawing.

I claim:

The ornamental design for a fence section, as shown and described.
